BROILER SHEET

Jeffrey M. Koblick, 1291 10th St.,
New Brighton, Minn. 55112

Filed Sept. 25, 1972, Ser. No. 291,893

Term of patent 14 years

Int. Cl. D7—04

U.S. Cl. D7—129

FIG. 1.

FIG. 2.

FIG. 3.

FIG. 1 is a top plan view of a broiler sheet showing my new design;

FIG. 2 is a side elevational view thereof; and

FIG. 3 is a partial cross-sectional view taken on an enlarged scale along line 3—3 of FIG. 1.

The bottom of the broiler sheet is flat except for the concentric rings of perforations, one of which being shown in FIG. 3.

I claim:

The ornamental design for a broiler sheet, as shown and described.
